PIEZOELECTRIC DEVICE

Charles E. Semple, Jr., Youngstown, Ohio

Application August 5, 1935, Serial No. 34,658

12 Claims. (Cl. 179—110)

This invention relates to the art of piezoelectric devices, and contemplates the use of a so-called "bimorph" crystal element.

As is well-known, a "bimorph" element consists of two crystals cemented together in such manner that one of the crystals contracts while the other expands when subjected to voltage. The crystals of such an element may be oriented in such manner that two diagonal corners of a crystal will turn down while the other two corners turn up when a voltage is applied. Conversely, the same element may be utilized to produce a voltage by the application of mechanical pressure to the element, as will be readily understood.

15 My device may be employed either as a speaker or microphone.

The present invention in its broad aspect contemplates the use of either a "torque" crystal element or a "bender" crystal element.

20 More specifically, this invention embodies a single "bimorph" element and a pair of diaphragms co-ordinated therewith in such manner as to produce highly desirable results with respect to both quality and out-put. This particular combination constitutes one object of my invention, and is a great improvement upon prior high grade devices in which there have been employed two crystals so arranged that the sound waves would impinge directly upon the crystals when employed, for instance, as a microphone. The possibility of using only one "bimorph" crystal, accordingly, constitutes an important object of the present invention.

Another object is to devise such a unit that can be produced at a very low cost.

A still further object is to devise such a unit that can be made of comparatively small size, while still possessing extremely high efficiency, so that it will be readily adaptable to uses and with advantages, either singly or in multiple, heretofore impossible.

Other objects will appear from the following description and claims when considered together with the accompanying drawing.

45 Referring to the drawing,

Fig. 1 is a perspective view of a "bimorph" Rochelle salt crystal element in which the two crystals are cemented together in such manner as to function as a "torque" element;

Fig. 2 is a perspective of one of the duplicate yokes employed for fastening the crystal to the diaphragms;

50 Fig. 3 is a perspective of one of the duplicate diaphragms;

Fig. 4 is a perspective of the housing member or support; and

Fig. 5 is a perspective view, broken away, illustrating the complete assembly of a microphone embodying my invention.

Referring now to the drawing in detail, the "bimorph" crystal element 1 is mounted centrally within the medial plane of the housing member 2, which may be made of Bakelite or other suitable material, and is arranged between the oppositely disposed duplicate, conical diaphragms 3. In the present illustration, it will be observed that the crystal element is of substantially square form with the four corners thereof squared off so as to facilitate engagement of the crystal element 15 at these four points with the slots 4 of the duplicate, substantially semi-circular, yoke members 5. Suitable adhesive material may be employed at these points of engagement between the yoke members and the crystal element, so as to render 20 the same more secure. These yoke members are formed as metal stampings and are arranged in planes at right angles to each other, with their projecting ears 6 extending out through the centrally disposed apertures 3a of the diaphragms 3. 25 The engagement of the ears 6 in the apertures 3a can be rendered more secure, if so desired, by means of solder at these points.

The outer marginal portions of the diaphragms 3 are reinforced by means of an annular groove 30 3b which is formed therein in the operation of stamping out the diaphragms which are made of suitable light weight flexible metal. The edge portions of the diaphragms are secured to the opposite sides of the annular housing member 2 35 by means of adhesive material or in any other suitable manner.

The electric terminals 7 extend through apertures 2a in the housing ring and are connected to the crystal element 1. Electrodes may be provided in the usual manner as desired.

It will be observed that in the present form of device, the same single "bimorph" element co-operates with the two diaphragms, the structure and arrangement of these parts being such that there is produced a double form of unitary device which is capable of greatly increased work. Hence there is obtained a greatly amplified effect with a single "bimorph" element.

When this device is used as a microphone, the 50 sound waves will be impinged against both diaphragms 3 which will transmit their vibrations to the crystal element 1, the movements of one diaphragm causing corresponding movement of two diagonally opposite corner portions of the crystal 55

element in the direction opposite to that in which the other diagonally opposite corner portions of the crystal element are simultaneously moved by the other diaphragm.

5 In carrying out my invention, different types of crystal elements may be employed, either "bender" or "torque", all of which modifications include a pair of oppositely disposed diaphragms, whereby it is possible to obtain a greatly heightened effect, whether the device be employed as a microphone or speaker, and likewise it is possible to produce a given desired effect with a device of considerably smaller proportions than has heretofore been possible. Likewise, in constructing a multiple unit assembly for a given capacity, my invention makes it possible to use fewer units than heretofore required. These advantages may be realized without any serious sacrifice in quality, the unit embodying my invention being capable of high fidelity in frequency response.

Because of the manner in which all possible effect of the crystal element is here utilized, I am able to produce maximum work in such a device. The structure and arrangement of the several parts, including the diaphragms and yoke members, makes it possible to obtain such a heightened effect with but a single crystal element. Furthermore, the structure involved is extremely simple and compact and the parts are of duplicate form. At the same time, the structure is readily assembled, it is of balanced form and arrangement and is extremely dependable and very efficient both in quantity and quality of work.

35 In this construction, the crystal element might be considered as a floating element suspended between the diaphragms by means of the yoke members. And the effects produced upon the two sides of the crystal element, are so co-ordinated by virtue of the particular connections provided, that there is obtained a greatly amplified result which is more than that to be expected from the combined effect of two devices of the ordinary single form and of this same size. Thus, 40 the co-ordination of the oppositely disposed diaphragms and the single centrally disposed crystal element, lends an unexpected and unaccountable additional amplification in the work performed.

50 The great saving in cost of manufacture constitutes another important advantage of my present improved device.

While the diaphragms are here shown of conical form, other forms may be employed. Also, 55 the crystal element, shown here as being of substantially square shape, may be of other shapes. Likewise, other details of my structure might be varied without departing from the spirit of my invention as herein set forth and claimed.

60 What I claim is:

1. A piezo-electric device comprising a single "bimorph" crystal element of polygonal slab form, diaphragms arranged upon opposite sides of the crystal element, and operative means of connection between said crystal element and said diaphragms, said means of connection being applied to individual pairs of diametrically opposite points of said crystal element.

2. A piezo-electric device comprising a single 70 "bimorph" crystal element of polygonal slab form, diaphragms arranged upon opposite sides of the crystal element, and operative means of connection between said crystal element and said diaphragms, said means of connection being applied to individual pairs of diametrically oppo-

site points of said crystal element, and said means of connection on opposite sides of said crystal element being operative in planes normal to each other.

3. A piezo-electric device comprising a single 5 "bimorph" crystal element of substantially rectangular slab form, diaphragms arranged upon opposite sides of the crystal element, and operative means of connection between said crystal element and said diaphragms, said means of connection being applied to individual pairs of opposite portions of said crystal elements.

4. A piezo-electric device comprising a single "bimorph" crystal element of substantially rectangular slab form, diaphragms arranged upon 15 opposite sides of the crystal element, and operative means of connection between said crystal element and said diaphragms, said means of connection being applied to individual pairs of diagonally opposite corner portions of said crystal 20 elements.

5. A piezo-electric device comprising a single "torque" "bimorph" crystal element of substantially square slab form, diaphragms arranged upon 25 opposite sides of the crystal element, and operative means of connection between said crystal element and said diaphragms, said means of connection being applied to pairs of diagonally opposite corner portions of said crystal element.

6. A piezo-electric device comprising a housing 30 ring member, duplicate conical diaphragms arranged upon and secured to opposite sides of said ring member, a single "bimorph" crystal element of substantially square slab form arranged in the medial plane of said ring member, and duplicate 35 substantially semi-circular yoke members each providing operative connection between one of said diaphragms and diagonally opposite corner portions of said crystal element.

7. A piezo-electric device comprising a single 40 "bimorph" crystal element, duplicate diaphragms arranged upon opposite sides of the crystal element, and duplicate operative means of connection between said crystal element and said diaphragms, said diaphragms being centrally connected to spaced points of said crystal element, and said crystal element being otherwise free.

8. A piezo-electric device comprising a single "bimorph" crystal element, substantially conical-shaped diaphragms arranged upon opposite sides 50 of the crystal element, and operative means of connection between said crystal element and said diaphragms, said means of connection consisting entirely in each of said diaphragms being centrally connected to two opposite points of said 55 crystal element, and the basal planes of said diaphragms and that of said crystal element being substantially parallel.

9. A piezo-electric device comprising a single 60 bimorph crystal element of polygonal slab form, diaphragms arranged upon opposite sides of the crystal element, and operative means of connection between said diaphragms and crystal element, the basal planes of said diaphragms and crystal element being substantially parallel, and said crystal element being supported solely by said means of connection.

10. A piezo-electric device comprising an open 70 form of housing member, diaphragms arranged upon and secured to opposite sides of said housing member, a single floating bimorph crystal element arranged within said housing member, and means providing floating operative connection between said diaphragms and said crystal 75

element, the basal planes of said diaphragms and crystal element being substantially parallel.

11. In a piezo-electric cell, a pair of diaphragms, a piezo-electric crystal entirely supported from 5 and between the diaphragms, the supporting means having a pair of supporting members extending from opposite points adjacent the periphery of the crystal, said supporting means being operably connected to one diaphragm, and a second supporting means having a pair of supporting members extending from opposite points adjacent the periphery of the crystal, said second supporting means being operably connected to the other diaphragm.

12. In combination, a single piezo-electric crystal, means responsive to sound waves, a floating connection between said crystal and sound-responsive means and comprising means for supporting the crystal at two points thereof on the 5 sound-responsive means, and means operatively engaged to the sound-responsive means and to the crystal at a third point not in line with the first two points whereby sound waves cause torsional movement of the crystal.
